TOP BURNER CLOSURE STRUCTURE

Claude E. Parker, Chicago, Ill., assignor to Gas Products Corporation, Chicago, Ill., a corporation of Illinois

Application March 30, 1940, Serial No. 326,883

15 Claims. (Cl. 126—39)

The present invention relates to improvements in closure or hearth structures adapted to be removably supported in a gas stove or range cooking tops in the burner openings of the top panel.

The instant application is a continuation in part of my copending application Serial No. 272,984, filed May 11, 1939. In said copending application I have described and claimed a novel form of cooking top structure in which a burner head, registering with a hole in the top panel of the stove, has above it an overlying hearth or closure structure apertured for the passage of flames from the burner head to a utensil; and which closure structure coacts with the head to define a novel system of secondary air supply passages to the flames. I have referred to the structure noted as a "closure structure" since it either alone or in conjunction with the burner head gives the stove top a generally closed appearance although, as noted, it does have openings in it for issuance of flames so as to achieve the high degree of efficiency peculiar to an open top style of stove in which the flames play directly on the utensil being heated. The particular closure structure shown, by way of exemplification, in said copending application is made in part of refractory material in order better to withstand the intense heat of the blanket of flames confined between it and the closely overlying utensil bottom as well as for other reasons incident to efficient and effective operation. This same closure structure, as well as certain modified forms thereof, have been illustrated herein. The present invention has primarily to do with improvements in the closure structure per se or, in other words, with a subcombination of the general cooking top structure disclosed in said copending application and in its broadest aspects embraces the use of closure structures made in one piece as well as those embodying a refractory or other separate element or elements on a metallic support.

Generally stated, it is an object of the invention to provide a novel closure structure of the character indicated which is of unitary form such that the whole structure and its associated utensil seating arrangement can be removed from the stove and handled as a unit.

Another object of the invention is to provide such a closure structure having a novel contour or shape such as efficiently to apply heat to an overlying utensil bottom and which will, however, impart to the stove top a finished and attractive appearance.

Another object is to provide a structure of the

type set forth of such character that effectual application of the heat of combustion to a utensil is accomplished while preventing direct flame impingement on the utensil supports, so as to protect the finish of the latter.

In its more specific aspects, it is an object of the present invention to provide a closure or hearth structure of the type indicated embodying one or more of the following features: (a) A novel interlocking arrangement between a plurality of refractory elements and a metal cradle or carrier for them such that the parts are normally held together as a unit for removal of the entire closure structure from the stove for cleaning, etc., but in such manner that the refractory elements can be readily detached, if desired, for purposes of replacement and the like; (b) a cradle having abrasion-resistant metal utensil supports on it adapted to perform the further function of holding in place a set of removable refractories; (c) a strong metal cradle arranged to protect a set of refractories on it from mechanical shock, as well as to support the same; and (d) a novel interlocking arrangement between the cradle and refractories for holding the latter in place without danger of breakage of the refractories due to inequalities in the coefficients of thermal expansion of the materials comprising the cradle and refractories, respectively.

Further objects and advantages of the invention will become apparent as the following description proceeds, taken in connection with the accompanying drawings in which:

Figure 1 is a plan view of a closure structure embodying the invention.

Fig. 2 is a transverse sectional view taken substantially along the line 2—2 in Fig. 1.

Fig. 3 is an exploded perspective view of the closure structure of Fig. 1.

Fig. 4 is an exploded perspective view of a modified form of closure structure embodying the invention.

Fig. 4^a is a transverse sectional view, on reduced scale, of the closure structure of Fig. 4.

Fig. 5 is a plan view of a further modified form of closure structure embodying the invention.

Fig. 6 is a sectional view taken substantially along the line 6—6 in Fig. 5.

Fig. 7 is a fragmentary side elevation of the structure of Fig. 5, showing the end of one of the utensil supports.

While the invention is susceptible of various modifications and alternative constructions, I have shown in the drawings and will herein describe in detail, the preferred embodiment, but

It is to be understood that I do not thereby intend to limit the invention to the specific form disclosed, but intend to cover all modifications and alternative constructions falling within the spirit and scope of the invention as expressed in the appended claims.

For purposes of exemplification the invention has first been shown (Fig. 1) and described herein as embodied in a closure or hearth structure comprising a generally disk shaped assembly adapted to be seated as a unit in a burner hole in the top panel over a gas burner head (not shown). The function of such a closure structure is, from an appearance standpoint, to conceal the underlying burner head and substantially to fill the aperture in the top plate so as to form a generally coplanar continuation of the top plate instead of leaving a more or less open and unsightly hole in it. From a thermal efficiency standpoint, the closure structure serves to confine beneath a closely spaced overlying utensil bottom a blanket of intensely hot flames, to reflect heat to the utensil bottom, and to store up heat which is subsequently radiated to the utensil bottom.

As a principal element the first illustrative closure structure includes (see Fig. 3) a metal cradle or carrier 10, with which are removably interlocked a plurality of structurally separate refractory elements 11 and 12, and having rigid with it a series of metal utensil supports 13. Also included in the assembly are three auxiliary metal supporting fingers 14, which cooperate with the cradle to hold the refractory elements in place on the latter as hereinafter set forth.

The cradle 10 is desirably made of cast iron and includes a circular border ring 15 with an upstanding annular flange 16 on it. The utensil supports 13 are, in the present instance, integral with the cradle and extend along three equidistant radii. It will be observed that the rounded outer ends or noses 17 of the utensil supports project laterally beyond the periphery of the cradle so as to form buffers. When, for example, a heavy cast iron skillet or pot is slid across the top of the stove onto the hearth it rides up on the adjacent utensil support nose and onto the top surfaces of the utensil supporting arms, thereby protecting the more fragile refractories from mechanical shock. On the cradle 10 intermediate the utensil supports are three inwardly projecting integral webs 18 on which the refractory elements 12 are seated (see also Fig. 2).

The refractory elements 11, 12 are arranged to present generally coplanar top surfaces forming a heat reflecting and confining hearth of shallow bowl shape in closely spaced relation beneath a utensil (not shown) seated on the supports 13. The refractory elements may be made of any suitable heat resistant material. Desirably they are made of ceramic material having a glazed vitric coating fused on it at a temperature of about 2500° F., or in other words, well above any temperature encountered in use even with flames from the gas burner lapping directly on it, a suitable material for the purpose being sold under the the trade name "Parkerite."

In the instant construction the refractory elements 11 are here shown (Fig. 3) as three in number and are fashioned in the form of elongated fingers lying along equidistant radii from the center of the assembly (see also Fig. 1). These elements 11 are notched at their outer ends as indicated at 19 in order to embrace and interlock with the upright base portions 20 of

the respective utensil supports 13. Each of the ceramic elements 11 underlies a respective one of the utensil supporting arms 13 throughout substantially the entire length of the latter, thereby thermally insulating it from an underlying burner. The burner head itself (not shown) may, if desired, be made in a three-arm form described and claimed in my copending application Serial No. 324,470, filed March 18, 1940, and arranged with one burner arm underlying each of the elements 11. To hold the refractory elements 11 in position the auxiliary metal fingers 14 are disposed in supporting relation beneath respective ones of them. The cradle 10 is notched as indicated at 21 (Fig. 3) to receive the outer ends of the metal supports 14 and the latter are fixed in place on the cradle by screws 22 (Fig. 2).

Intermediate the finger shaped elements 11 are located the other three refractory elements 12 (Fig. 1). These elements 12 are generally sector shaped and present arcuate inner edges. The inner ends of the finger shaped elements 11 are enlarged in a lateral direction (Fig. 1) so as to present complementary arcuate edges spaced from the inner edges of the elements 11 and cooperating therewith to define elongated arcuate slots 23 of substantially uniform width from end to end, in the closure structure through which flames from an underlying burner head may issue. It will be observed that the intermediate elements are shallowly dished downward and inward so as to receive above them flames projected laterally outward through the slots 23. On the surfaces of the elements 12 are radially extending ribs 26 which direct the flames toward the periphery of the unit and which incandesce in the intense heat to which they are subjected to radiate heat to an overlying utensil. Similarly, the elements 11 are provided with incandescent ribs 27 along their marginal edges which border the flame slots 23.

Further flame apertures in the hearth are formed between the inner edges of the refractory fingers 11, which are opposed to each other (Fig. 1). It will be seen that they are spaced apart to define an open center 28 connected through slots 29 with the main slots 23, and beneath which openings 28, 29 may be located a suitable center simmer burner or the like (not shown).

By shaping the elements 11, 12 as set forth, particularly with the dished intermediate elements 12 leading out from the flame slots 23 and separated by higher finger elements 11 on which the utensil seats 13 are located, the flames issuing through the slots 23 are effectually distributed over the bottom of a utensil resting on the seats 13. Since these slots 23 are, however, curved at their outer ends to follow along the sides of utensil supporting elements, the flames issuing through the slots are directed generally away from the utensil supports and never impinge on them so that their finish is not impaired. Not only is the heat confined in a blanket of high temperature beneath the utensil but the glossy vitric surfaces of the refractory elements intercept its downward flow and reflect it effectually to the utensil bottom. Heat which is gradually stored in the hearth is subsequently radiated to the utensil even after the burner is turned off so that cooking can be continued at such time and maximum efficiency achieved. In other words, a so-called fast start in cooking is achieved because the hearth absorbs heat but very slowly, most of it being directed initially

to the utensil, but the excess which is gradually stored in the hearth can subsequently be transmitted by radiation to the utensil to prolong cooking even after the burner is turned off. Despite the intense heat to which the elements 11, 12 are subjected in the course of such operation they will, without deterioration withstand the same, in view of their construction heretofore set forth.

Of particular importance in the present instance is the arrangement for holding the various ceramic elements 11, 12 in assembled relation on the cradle 10 so that the entire closure structure may be handled as a unit without danger of inadvertent dislodgment of any of the elements. Though the refractory parts 11, 12 are structurally separate, as heretofore described, for the sake of simplicity in their original manufacture and so that they can, if necessary, be removed or replaced, the whole assembly is normally unitary. As a result the closure structure can be readily lifted from the stove top as a unit, either for washing and cleaning of the cover itself, or for cleaning or adjustment of interiorly located parts in the stove such as the burner head.

To hold the intermediate refractory elements 12 in place on the cradle 10 these elements are interlocked at their ends with the elements 11. For this purpose integral shoulders or ribs 24 (Fig. 3) are fashioned on the ends of each of the elements 12 while complementary ribs or shoulders 25 are fashioned at the sides of the outer end portions of the elements 11. When the parts are disposed in assembled relation the elements 12 rest on the cradle webs 18 and are held against displacement upwardly by the overlying interlocking projections or ribs 25 on the elements 11. These elements 11 are in turn interlocked with the cradle by the utensil supports 13. Thus the engagement of the notched ends of the elements 11 with the supports prevents their displacement laterally in the plane of the cradle while the overlying arms 13 prevent the fingers 11 from being displaced upwardly. Finally, the underlying auxiliary fingers 14 hold the fingers 11 against downward displacement. The peripheral flange 16 on the cradle holds the elements 12 against movement radially outward of the cradle. In this connection it should be noted in Fig. 2 that the elements 12 are peripherally grooved so as to receive the flange 16 and are thus seated snugly in the more or less cup shaped cradle.

It will thus be seen that all of the elements of the closure structure are thoroughly interlocked with each other so that the structure can be handled as a unit and turned in any direction without possibility of having one of the structurally separate elements fall off. On the other hand, the use of interfitting or interlocking joints between all of the parts of dissimilar material makes possible the use of sufficiently wide clearances between their abutting parts as to permit of inherently different expansions when heated without danger of cracking the refractories. In this connection it should be noted that the only screws used are the screws 22 which connect only metal parts, viz., the cradle 10 and metal fingers 14, as distinguished from connecting a refractory part and a metal part.

In assembling the closure structure of Figs. 1 to 3 the intermediate refractory elements 12 are seated on the cradle webs 18. The finger shaped refractory elements 11 are then pushed into

place beneath the utensil supports 13 in a direction longitudinally outward of the latter. The ribs 24, 25 are thus brought into interlocking relation so that the elements 11 hold the intermediate elements 12 in place. Then, to complete the assembly the metal fingers 14 are screwed in place beneath the refractory fingers 11. By these simple manipulations the entire structure is assembled as a firmly interlocked unit.

In Fig. 4 I have shown a modified form of hearth or closure structure also embodying the invention. It differs from that of Figs. 1 to 3, described above, primarily in that instead of using refractory fingers like the elements 11, overlaid by separate metal utensil supporting fingers, these two elements have been combined in the form of metal fingers 13^a. These elements 13^a, together with a single set of intermediate refractory elements 12^a are removably supported on a cradle 10^a.

In this instance the cradle 10^a is much like the cradle 10 described above, being made of cast iron or the like and including a circular border ring 15^a with an upstanding annular flange 16^a on it. Projecting inwardly from the border ring 15^a are webs 18^a, which carry the refractory elements 12^a. In this construction the utensil supports are removably, though rigidly, attached to the cradle. For this purpose bosses 20^a are formed on the cradle 10^a at three equally spaced points intermediate the webs 18^a. Suitable screws (Fig. 4^a) are inserted through holes 22^a (Fig. 4) in these bosses and are threaded in the butt portions of the utensil supporting fingers 13^a to hold the same in position.

The intermediate refractory elements 12^a are of substantially the same form and construction as the elements 12 of Figs. 1 to 3, and are desirably made of the same glazed ceramic material heretofore described. In this instance, however, they have been shown as being of somewhat smoother or less irregular contour having but two ribs 26^a on each of them.

The utensil seating or supporting elements 13^a may be made of cast metal or the like and plated, enameled or polished to give them a decorative and pleasing finish. Adjacent their outer end portions are provided laterally projecting ribs or wings 25^a which overlie and interlock with ribs 24^a on the ends of the intermediate elements 12^a so as to hold the same in position on the cradle 10^a in the same general manner as heretofore described for the interlocking parts in the device of Figs. 1 to 3.

To form three generally arcuate flame slots arranged in triangular configuration, like the slots 23 of Fig. 1, the inner edges of the intermediate refractory elements 12^a are again made generally arcuate in form. In the present instance, however, the inner ends of the metal fingers 13^a are splayed or enlarged laterally to match the curvature of the inner edges of these elements 12^a just as were the ends of the refractory fingers 11 in Fig. 1.

In assembling the closure structure of Fig. 4 the refractory elements 12^a are seated on the webs 18^a of the cradle. The metal fingers 13^a are then seated on the bosses 20^a and screwed to the latter. When so positioned the wings 25^a on the fingers 13^a interlock with the elements 12^a and hold the same fixedly in position on the cradle so that the whole structure can be readily handled as a unit without danger of inadvertent dislodgment of any of the parts.

A second modified form of closure structure embodying the invention has been shown in Figs. 5 to 7. In this particular instance no ceramic material is used but, instead, the whole unit is made in the form of a single integral casting or molding. It will be observed, however, that its top surface is of substantially the same contour as that for the cover structures heretofore described. Since no refractories are used it is unnecessary to provide a separate cradle element. In the present instance the closure structure embodies three radially extending finger portions 13^b of substantially the same surface contour as the fingers 13^a described above. The top surfaces of these fingers are in the form of longitudinal ridges on which a utensil may be seated, the outer end portions of the ridges being elevated above the rim of the bowl (Fig. 7). If desired, in order to simplify the provision of a contrasting finish on the finger portions 13^b and the remainder of the bowl, the fingers can be made as separate metal castings screwed to the bowl like the fingers 13^a described above. Intermediate these fingers portions 13^b and integral therewith are intermediate portions 12^b of shallow dish or bowl shape and corresponding generally to the contour of the intermediate elements 12 and 12^a heretofore described although they are preferably dished somewhat more deeply inasmuch as they are made of metal and, hence, cannot well withstand direct flame impingement without burning off their finish. On these intermediate portions 12^b are raised bosses 26^b, set well back from the center of the structure so as to be out of its hottest portion and forming auxiliary or intermediate utensil supports.

It will be observed in Fig. 5 that the inner edges of the intermediate portions 12^b of the structure are convexly curved while the inner ends of the utensil supporting fingers 13^b are splayed outwardly in complementary form to define flame emission openings 23^b through which flames from an underlying burner head may issue.

The cover structure of Figs. 5 to 7 is desirably made of cast iron and has a porcelain enamel finish. Since it is fashioned as a single unit it can be readily handled during removal for washing, etc. It, like the other closure structures heretofore described, substantially closes the burner aperture in the stove top plate, from an appearance standpoint, so as to give it an appearance of smooth, over-all glossy finish and yet is apertured for the issuance of flames from an underlying burner head so that they can play directly on a utensil seated on the fingers 13^b. Since these utensil supporting fingers are desirably formed integrally with the mass of metal which constitutes the remainder of the closure structure or at least fixed rigidly to it, heat imparted to them from the flames is distributed throughout the closure structure, thereby insuring a sufficiently low over-all temperature for the structure, that liability of burning off of its finish is obviated.

In each of the several illustrated embodiments of my invention the three spaced radial portions of the cover structure coact to form a central section adapted to overly and substantially conceal an underlying burner, while the three intervening portions cooperate in the formation of an outer section having downwardly offset surfaces over which the hot gases from the burner may discharge through outlet means consisting of slots 23 or 23^b. While the several cover

structures illustrated are in a form adapted for use with a burner of triangular shape such as that disclosed in my copending application Serial No. 272,984, it is understood that cover structures for use with burners of other shapes may be provided by those skilled in the art without departing from the spirit and scope of my invention as defined by the appended claims.

I claim as my invention:

10. A closure unit of the type set forth comprising, in combination, a plurality of radially extending portions presenting utensil seating surfaces of elongated ridge form on their tops, means intermediate said radial portions presenting wide top surfaces dished shallowly downward and inward, the inner edges of said surfaces being convexly curved and the inner ends of said radial portions being splayed laterally outward to match generally the curvature of said edges but spaced therefrom to define therewith elongated slots for the issuance of flames through said slots and over said top surfaces.
15. A closure unit of the type set forth comprising a generally shallow dish shaped unitary structure having rigid with it elongated utensil supports extending radially inward toward its center and presenting utensil seating surfaces spaced above the perimeter of the dish, and said dish having a plurality of slots therein intermediate said supports with the ends of the slots curved outwardly toward the edge of the dish and lying along the adjacent sides of the supports for the emergence of flames through such slots and over the portions of the dish intermediate the supports.
20. A closure unit of the type set forth comprising a generally ring shaped metallic cradle open in its central portion, a plurality of elongated finger elements projecting radially inward from the periphery of said cradle toward its center, means removably fixing said finger elements to the cradle, said finger elements having utensil seating means on their tops, intermediate refractory elements seated on the cradle between
25. adjacent ones of said finger elements, and said finger elements having lateral projections on their outer end portions overlying complementary formed portions of the ends of the intermediate elements in interlocking relation therewith to hold the same on the cradle.
30. A closure unit of the type set forth, comprising a generally ring shaped metallic cradle open in its central portion, a plurality of elongated finger elements projecting radially inward from the periphery of said cradle toward its center, means removably fixing said finger elements to the cradle, said elements having utensil seating means on their tops, intermediate refractory elements seated on the cradle between adjacent ones of said finger elements, said finger elements being shallowly dished downward and inward toward the center of the unit and having convex inner edges, the inner ends of said finger elements being enlarged laterally to conform
35. generally to the curvature of said convex edges but disposed in spaced relation thereto to define therewith slots for the emergence of flames over said dished intermediate elements, and said finger elements having lateral projections on their outer end portions overlying complementary shaped portions of the ends of the intermediate elements in interlocking relation therewith to hold the same on the cradle.
40. A closure unit of the type set forth, comprising a generally ring shaped metallic cradle open in its central portion, a plurality of elongated finger elements projecting radially inward from the periphery of said cradle toward its center, means removably fixing said finger elements to the cradle, said elements having utensil seating means on their tops, intermediate refractory elements seated on the cradle between adjacent ones of said finger elements, said intermediate elements being shallowly dished downward and inward toward the center of the unit and having convex inner edges, the inner ends of said finger elements being enlarged laterally to conform
45. generally to the curvature of said convex edges but disposed in spaced relation thereto to define therewith slots for the emergence of flames over said dished intermediate elements, and said finger elements having lateral projections on their outer end portions overlying complementary shaped portions of the ends of the intermediate elements in interlocking relation therewith to hold the same on the cradle.
50. A closure unit of the type set forth, comprising a generally ring shaped metallic cradle open in its central portion, a plurality of elongated finger elements projecting radially inward from the periphery of said cradle toward its center, means removably fixing said finger elements to the cradle, said elements having utensil seating means on their tops, intermediate refractory elements seated on the cradle between adjacent ones of said finger elements, said intermediate elements being shallowly dished downward and inward toward the center of the unit and having convex inner edges, the inner ends of said finger elements being enlarged laterally to conform
55. generally to the curvature of said convex edges but disposed in spaced relation thereto to define therewith slots for the emergence of flames over said dished intermediate elements, and said finger elements having lateral projections on their outer end portions overlying complementary shaped portions of the ends of the intermediate elements in interlocking relation therewith to hold the same on the cradle.
60. A closure unit of the type set forth, comprising a generally ring shaped metallic cradle open in its central portion, a plurality of elongated finger elements projecting radially inward from the periphery of said cradle toward its center, means removably fixing said finger elements to the cradle, said elements having utensil seating means on their tops, intermediate refractory elements seated on the cradle between adjacent ones of said finger elements, said intermediate elements being shallowly dished downward and inward toward the center of the unit and having convex inner edges, the inner ends of said finger elements being enlarged laterally to conform
65. generally to the curvature of said convex edges but disposed in spaced relation thereto to define therewith slots for the emergence of flames over said dished intermediate elements, and said finger elements having lateral projections on their outer end portions overlying complementary shaped portions of the ends of the intermediate elements in interlocking relation therewith to hold the same on the cradle.
70. A closure unit of the type set forth, comprising a metal supporting cradle, a plurality of
- 75.

refractory hearth elements removably seated on said cradle, and means including a plurality of metal utensil supporting fingers rigid with said cradle and above the refractories and interlocked with the latter for holding the same in position on said cradle.

6. In a closure unit of the type set forth, the combination of a generally ring shaped metal cradle, metallic utensil-seating fingers fixed on said cradle and projecting radially inward toward its center from spaced points about its periphery, a plurality of refractory finger elements disposed beneath respective ones of said utensil-seating fingers, means for releasably clamping said refractory fingers against the under sides of the utensil-seating fingers, intermediate refractory elements seated on the cradle in the spaces intervening between successive ones of the refractory fingers, and the outer end portions of said refractory fingers having integral lateral projections thereon overlying complementary shaped end portions of said intermediate elements in interlocking relation therewith to hold the intermediate elements against dislodgment from the cradle.

7. In a closure unit of the type set forth, the combination of a generally ring shaped metal cradle, metallic utensil-seating fingers fixed on said cradle and projecting radially inward toward its center from spaced points about its periphery, a plurality of refractory finger elements disposed beneath respective ones of said utensil-seating fingers, means for releasably clamping said refractory fingers against the under sides of the utensil-seating fingers, intermediate refractory elements seated on the cradle in the spaces intervening between successive ones of the refractory fingers and shallowly dished downward and inward toward the center of the unit, the inner edges of said intermediate elements being convexly curved, the inner end portions of said refractory fingers being enlarged laterally and spaced from said inner edges of said intermediate elements to define therewith slots for the passage of flames through such slots and over said dished intermediate elements, and the outer end portions of said refractory fingers having integral lateral projections thereon overlying complementary shaped portions of said intermediate elements in interlocking relation therewith to hold the intermediate elements against dislodgment from the cradle.

8. In a closure unit of the type set forth, the combination of a metal cradle including a border ring, a plurality of metal utensil-seating fingers projecting radially inward toward the center of the ring from circumferentially spaced points on it and joined to the ring at their outer ends by upstanding posts, refractory finger elements underlying respective ones of the metal fingers and notched at their outer ends to embrace said posts in interlocking relation therewith, intermediate refractory elements seated on said cradle in the spaces intervening between successive ones of the refractory fingers, and means including interlocking projections on the adjacent portions of said refractory fingers and intermediate elements for releasably holding the latter in position on the cradle.

9. In a closure unit of the type set forth, the combination of a metal cradle including a border ring, a plurality of metal utensil-seating fingers projecting radially inward toward the center of the ring from circumferentially spaced

points on it, means for releasably fixing the outer end portions of said fingers to said ring, intermediate refractory elements seated on said cradle in the spaces intervening between successive ones of said fingers, and means including lateral projections on the outer end portions of said fingers overlying complementary shaped end portions of said intermediate elements in interlocking relation therewith to hold the intermediate elements against dislodgment from the cradle.

10. In a closure unit of the type set forth, the combination of a metallic cradle including a border ring, a plurality of metal utensil-seating fingers projecting radially inward toward the center of the ring from circumferentially spaced points on it, means for releasably fixing the outer end portions of said fingers to said ring, intermediate refractory elements seated on said cradle in the spaces intervening between successive ones of said fingers, said intermediate elements being shallowly dished downward and inward toward the center of the cradle and the inner edges of said intermediate elements being convexly curved, means including interlocking projections on the adjacent portions of the said fingers and intermediate elements for releasably holding the latter in position on the cradle, and the inner end portions of said metal fingers being enlarged laterally to provide edges generally complementary to the inner edges of said intermediate elements and spaced therefrom, thereby to define slots for the emergence of flames through such slots and over the dished intermediate elements.

11. A closure unit of the type set forth comprising a single integral molded dish of shallow contour, said dish having a plurality of radial ridges raised thereon to form utensil seats, the longitudinal top surface of said ridges being elevated at their outer end portions above the rim of the dish, said dish having a plurality of slots in its central portion disposed respectively between successive ones of said ridges, the ends of said slots being curved outwardly toward the perimeter of the dish and lying along the sides of said ridges, the outer edges of said slots being depressed for the emergence of flames through said slots and over the portions of the dish intervening between said utensil-supporting ridges.

12. In a closure unit of the type set forth comprising, in combination, a plurality of radially extending portions presenting utensil seating surfaces of elongated ridge form on their tops, means intermediate said radial portions presenting wide top surfaces dished shallowly downward and inward, the inner edges of said surfaces being convexly curved and the inner ends of said portions being splayed laterally outward to match generally the curvature of said edges but spaced therefrom to define therewith elongated slots for the issuance of flames through said slots and over said top surfaces, and the inner ends of said radially extending portions coacting to define a central opening in the closure unit for the issuance of flames centrally of the unit.

13. A closure unit adapted to be removably seated in the burner opening of a stove top panel or the like and comprising an integral metallic disk having a border portion presenting a top surface of substantial lateral width and sloping downwardly from its perimeter inwardly toward the center, a plurality of circumferentially spaced radial portions rigid with said border portion and extending longitudinally inward from points located above the perimeter of said border portion toward the center of the unit, and utensil

supporting ridges on the radial portions, said radial portions being made of a width substantially greater than said ridges and coacting with the inner edges of the border portion to define flame-emission slots.

14. A cover unit for a gaseous fuel burner comprising, in combination, a circular disk having circumferentially spaced radially extending portions presenting utensil seating surfaces and other portions intervening between said radial portions and presenting wide top surfaces disposed on a plane below said radial portions, said disk having apertures therein opening outwardly along the sides of said radial portions and

adapted to permit of the discharge over said intervening portions of the gases of combustion.

15. A burner cover unit for a gaseous fuel cook stove, comprising a central section providing utensil seating surfaces, and an outer section presenting wide top surfaces offset downwardly from the top of the central section and extending outwardly therefrom, and outlet means at the side edges of said central section and above the inner edges of the outer section for the escape of products of combustion outwardly above said outer section.

CLAUDE E. PARKER.
